UNITED STATES PATENT OFFICE.

ERASTUS B. BARKER, OF NEW YORK, N. Y., ASSIGNOR TO E. AND H. T. ANTHONY & CO., OF SAME PLACE.

IMPROVEMENT IN CAMERAS.

Specification forming part of Letters Patent No. **170,465**, dated November 30, 1875; application filed November 8, 1875.

To all whom it may concern:

Be it known that I, ERASTUS B. BARKER, of the city and State of New York, have invented an Improvement in Camera-Boxes, of which the following is a specification:

Plate holders or carriages have been made to slide across the back of the camera-box, and in some instances conical rollers have been employed to support such holder, but there is considerable friction in moving a conical roller along in a straight line, and the surface of the holder is pressed against the back of the camera and causes unnecessary friction.

My invention consists in combining with a plate-holder supporting-rollers, that are arranged to cause the holder to bear against the back of the camera-box, and rollers that determine the approach of such holder to the camera-box and relieve the friction. At the same time the surface of the holder is sufficiently close to that of the box as to prevent light reaching the plate.

In the drawing, Figure 1 is a front view, and Fig. 2 is a longitudinal section, of a portion of said camera-box.

a represents the back of the camera-box, and *b* is the plate-holder, in the form of a frame, adapted to receive the photographic plate. These parts are of any usual character.

There is a sill or bottom flange, *c*, at the lower edge of the plate holder or slide *b*, and also a guide-rib, *d*, at the upper part of such holder at the back thereof, which rib *d* slides behind the tongue *d'* that is formed at the edge of the offset in the back *a* of the camera-box.

There are rollers *e* beneath the flange or sill *c*. These rollers are preferably upon the stationary studs *f*, but they might be upon the flange or sill *c*, and run upon a stationary flange pro-

jecting at the back of the camera. The position of these rollers is such that, the weight of the plate-holder being between them and the camera, tends to press the plate-holder toward the back of the camera; and hence the plate-holder will be kept in contact or toward the camera-box, and there will not be any opening to admit light, and the plate-holder will move with but little friction. But as an additional means for lessening friction, the rollers *i* are applied at the top of the plate-holder frame, and bear against the back of the camera-box, and, if desired, similar rollers can be applied at the lower part of the plate-holder.

By this construction the plate-holder is sufficiently free to be moved with ease, and there is no risk of the parts being retained by friction, but the holder can be moved freely one way or the other in taking two pictures upon one plate, without disturbing the camera-box. The stop *l* is applied as usual to limit the movement of the plate-holder.

I do not claim rollers upon which the plate-holder carriage is suspended. These, however, do not lessen the friction in a horizontal direction of the carriage against the back of the camera-box.

I claim as my invention—

The combination, with the plate-holder carriage and ledge or sill *c*, of the rollers *e* below that sill, and the rollers *i* at the back of the carriage, substantially as and for the purposes set forth.

Signed by me this 4th day of November, 1875.

ERASTUS B. BARKER.
